POLO MALLET HEAD

Filed Nov. 21, 1931.

UNITED STATES PATENT OFFICE

HANS P. NELSON, OF GRANTWOOD, NEW JERSEY

POLO MALLET HEAD

Application filed November 21, 1931. Serial No. 576,582.

The subject-matter of the present invention relates to game apparatus and specifically has to do with an improved mallet head used in connection with the game termed "Pony polo".

Heretofore, it has been customary to construct these mallet heads from substantially non-yieldable material, such as wood, or the like, which are oftentimes relatively heavy in weight and which suffer materially by constant contact with the ball used in the game.

One of the chief objects of the present invention is to provide a mallet head which possesses sufficient body weight for the purposes to which it is put and which is sufficiently resilient to absorb repeated blows without experiencing undue wear.

Another aim is to provide a mallet head which is composed of relatively hard rubber having cavities or chambered portions adapted to receive an expandable fluid, such as air, for the purpose of rendering the same relatively stiff for the purposes indicated.

The invention is further featured by the arrangement of the cavities within the body portion of the head whereby the striking or central portion of the latter is presented to have sufficient strength to endure the shocks to which it is subjected.

An important object of the invention is to provide an inflatable mallet head and whose inflation serves to anchor a mallet shaft or handle therein.

Still another object is to provide means whereby an expandable fluid, such as air, may be entered into the cavities of the head and maintained therein, under pressure.

With these objects in view, together with others which will appear as the description proceeds, the invention resides in the novel formation, combination, and arrangement of parts, all as will be described more fully hereinafter, illustrated in the drawing, and particularly pointed out in the claims.

In said drawing:

Fig. 1 is a central longitudinal sectional view of a mallet head constructed in accordance with my invention.

Fig. 2 is a transverse sectional view taken on the line 2—2 of Fig. 1.

Fig. 3 is a central longitudinal sectional view of a slightly modified form of mallet head.

Fig. 4 is a fragmentary sectional view taken on line 4—4 of Fig. 3.

Referring now more in particular to the accompanying drawing, wherein like characters of reference denote similar parts throughout the several views, let 5 indicate the body portion of a mallet head, as shown in Figs. 1 and 2, wherein it will be observed said body portion presents a double tapering formation extending in opposite directions from the central or striking portion of said head, said head having the usual opening 6 for the reception of a shaft or handle, (not shown). As mentioned hereinbefore, said head is to be constructed of resilient and expandable material, such as rubber, and the general fabrication may be somewhat similar to that employed in the manufacture of automobile tires, and as shown in Fig. 2, a layer of canvas 7 may be embedded in the material, or a plurality thereof, so that some reinforcement may be present to resist undue expansion of said head when inflation occurs. Said head is provided with cavities 8 and 9, each leading from the ends of said head and each terminating in spaced relation to said opening 6, as shown in Fig. 1, said cavities having their ends sealed by valve elements 10 and 11. In view of the aforesaid arrangement it will be seen that chambers are defined within the body portion of said head, said chambers being adapted to receive air, under pressure, whereby said head is inflated and maintained in a rigid and stiff condition, for the purposes specified hereinbefore.

Each of said valve elements 10 and 11 comprises a body portion 12, having a bore 13 extending into a coaxial chamber 14, said chamber being closed by a cap 15, which is provided with a bore 16, whereby a clear passage is had longitudinally of said body portion 12 and cap 15. The insertion of a nozzle of an air line causes the ball valve 17 to be unseated from the position shown in Fig. 1, thus permitting the passage of the air through the bores and chamber to the cavities 8 and 9.

within said head portion. When sufficient air has been introduced, the nozzle is removed whereupon the ball valve 17 is re-seated, as shown in Fig. 1, and the escape of the air 5 within the cavities is prevented. It will be seen that this inflation of the body portion causes sufficient expansion thereof whereby the valve elements are securely positioned as indicated and whereby the handle inserted in 10 the opening 6 is firmly held in place.

In Figs. 3 and 4, I have shown a slight modification wherein a single valve element 18 is employed. This valve element is similar 15 to the ones just described and hence the same reference numerals have been applied. The body portion 19, having the usual opening 20 for the reception of a handle, is provided with a chamber 21 at one end and a cavity 22 at the other extremity, the latter being sealed 20 by the valve element 18, as explained hereinbefore. As a single valve element is employed it is necessary to provide means for the passage of the inflating fluid from the cavity 22 to the chamber 21, said means including a bore 23 and a bore 24, which extend 25 from the chamber 21 and cavity 22, respectively, both entering annular groove 25 arranged in the wall of said opening 20.

It is obvious that when a handle is inserted 30 in the opening 20 that groove 25 now presents a passageway which cooperates with said bores 23 and 24 to afford communication between said chamber 21 and cavity 22, and it is manifest that as the ball valve 17 35 is unseated by the entrance of the air through the valve element 18, as aforesaid, said air eventually fills both the cavity and chamber and when sufficient air has been introduced said head 19 is expanded and stiffened, whilst 40 the material of the head adjacent the central portion thereof tightly embraces the handle which will be inserted in said opening 20. Obviously, this engagement precludes the danger 45 of the escape of the air at this point of contact.

From the foregoing it will be seen that I have provided an article which is admirably adapted to serve its purpose. The head is relatively light, yet of sufficient density to 50 impart the necessary driving blow to a ball,

and it is obvious that the nature of the material used in the construction of the head prevents the entrance of moisture and its attendant deteriorating effect.

While the present is a disclosure of the 70 preferred embodiments of the invention, it is to be understood that the invention is not limited thereto, as various changes in the minor details of construction, proportion and arrangement of parts may be resorted to without departing from the spirit of the invention 75 as defined in the appended claims.

I claim:

1. A mallet head composed of expandable material and presenting a chamber and a cavity therein, there being an opening in said head for the reception of a handle and a groove arranged in the walls of said opening, each of said chamber and cavity being in communication with said groove when a handle is inserted in said opening and means positioned in said cavity whereby an expandable fluid may be passed to said cavity and into said chamber to stiffen said head and to expand the material adjacent said opening. 80 85 90

2. A pony polo mallet head of the class described, composed of expandable material and presenting internally thereof a chamber and a cavity arranged in spaced longitudinal relation in the opposite ends of said head and having an angular opening centrally and transversely arranged in said head between said chamber and said cavity for the reception of a handle therein, there being a bore providing communication to and from said 100 chamber and said cavity when said handle has been inserted within said angular opening, valve means positioned at one end of said head, communicating with said cavity, whereby an expandable fluid, under pressure, may enter said cavity and therefrom pass through said bore into said chamber, thus inflating both chamber and cavity evenly, and thereby providing a firm and air-tight grip upon the inserted portion of said handle, thus causing 105 an inflation of a sufficiency in said chamber and said cavity to maintain the exterior contour of said head by said inflation. 110 115 120
